(57) **CLAIM**

The ornamental design for an interlocking container, as shown and described.

DESCRIPTION

FIG. 1 is a top perspective view of an interlocking container, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top perspective view of the interlocking container, shown in a first used condition; and,

FIG. 9 is a top perspective view of the interlocking container, shown in a second used condition.

The even sized broken lines showing other interlocking containers in FIGS. 8 and 9 depicts environmental subject matter that forms no part of the claimed design, while the remaining even sized broken lines shown in the drawings depict the portions of the interlocking container that form no part of the claimed design.

The alternating sized broken lines shown in the drawings depict the bounds of the interlocking container that form no part of the claimed design.
